UNITED STATES PATENT OFFICE

JOSEPH W. BEESON, OF EAST ST. LOUIS, ILLINOIS, ASSIGNOR TO JOHN E. CARSON,
OF BELLEVILLE, ILLINOIS

CIGAR VENDING MACHINE

Application filed December 29, 1928. Serial No. 329,275.

This invention appertains to coin controlled article dispensing machines and more particularly to a cigar vending machine, which is so constructed as to afford a clear 5 vision of the package or container of the cigars, showing all stamps, brands, caution notices and the like.

One of the primary objects of the present invention is to provide a cigar vending machine in which the cigars are vended directly 10 from the original package or container and in such a manner as to prevent clogging of the machine.

Another salient feature of the invention is 15 to provide a coin controlled cigar vending machine in which the coin deposited performs the function of a key locking the operating plunger with a slide delivering mechanism, whereby upon operation of the 20 plunger the slide mechanism will automatically deliver a single cigar to the front of the machine.

A further object of the invention is the 25 provision of a novel slide mechanism for cigar vending machines including a slide plate mounted between suitable guide members, the plate having means for receiving a single cigar when in its normal retracted position and having a plunger slidably 30 mounted adjacent thereto with novel means for connecting the plunger with the slide plate by the depositing of a coin, the plunger and plate forming means for gripping and holding the coin in operative position, so 35 that upon movement of the plunger the slide plate will be operated therewith, carrying a cigar and coin above suitable release slots, the release slot for the cigar having communication with a delivery chute leading to 40 the front of the machine, and the coin slot having communication with a coin chute leading to the rear of the machine and into a suitable coin receptacle.

A further object of the invention is the 45 provision of novel means for guiding the slide plate during its travel and novel means for cutting off the flow of cigars from the box or container during the forward movement of the slide plate to a cigar ejecting position.

50 A further object of the invention is the

provision of novel means for supporting a cigar box or container within the dispensing machine, said supporting means being adjustable within certain limits to receive different sizes of cigar boxes.

A still further object of the invention is to provide a coin controlled cigar vending machine of the above character, which will be durable and efficient in use, one that will be simple and easy to manufacture, and one 60 which can be placed upon the market at a reasonable cost, and which will be entirely fool-proof in its operation.

With these and other objects in view, the 65 invention consists in the novel construction, arrangement and formation of parts, as will be hereinafter more specifically described, claimed, and illustrated in the accompanying drawings, in which drawings:

Figure 1 is a front elevation of the complete cigar vending machine constructed in accordance with my invention;

Figure 2 is a horizontal section through the same taken on the line 2—2 of Figure 1 looking in the direction of the arrows;

Figure 3 is a side elevation of the complete cigar vending machine;

Figure 4 is a vertical section through the machine taken on the line 4—4 of Figure 1 looking in the direction of the arrows illustrating the position of the slide plate for receiving a cigar from the original cigar box or container;

Figure 5 is a horizontal section through the machine taken on the line 5—5 of Figure 4 illustrating the top or cover plate for the slide mechanism;

Figure 6 is a horizontal section taken on the line 6—6 of Figure 4 looking in the direction of the arrows illustrating the slide and plunger mechanism in their normal inoperative positions for receiving a cigar from the cigar box and a coin from the coin receiving chute;

Figure 7 is a fragmentary vertical section through the machine taken on the line 7—7 of Figure 6 looking in the direction of the arrows illustrating the novel slide mechanism and showing the same in its normal po-

sition for receiving a cigar from the cigar box;

Figure 8 is a similar view showing the slide mechanism in its forward position for permitting the ejecting of a cigar through the delivery chute;

Figure 9 is a detail fragmentary section taken on the line 9—9 of Figure 7 looking in the direction of the arrows illustrating the parts in position for receiving a coin;

Figure 10 is a detail fragmentary vertical section taken on the line 10—10 of Figure 6 looking in the direction of the arrows showing the slide and plunger mechanisms in position for receiving a coin;

Figure 11 is a similar section showing the plunger and slide mechanisms locked together by the coin and in their forward cigar ejecting positions, the coin being still held between the plunger and the slide mechanisms;

Figure 12 is a fragmentary horizontal section taken on the line 12—12 of Figure 10 looking in the direction of the arrows illustrating the novel plunger and slide mechanisms, the same being in positions for receiving a coin;

Figure 13 is a fragmentary transverse section through the machine in a vertical plane taken on the line 13—13 of Figure 6 looking in the direction of the arrows showing the parts in their normal positions for receiving a coin, and

Figure 14 is a detail sectional view showing the friction guide member for engaging the slide plate for taking up any lost motion therein.

Referring to the drawings in detail, where in similar reference characters designate corresponding parts throughout the several views, the letter A generally indicates my cigar vending machine which comprises a casing B of any suitable design or form and preferably ornamented or treated to present a pleasing and attractive appearance.

In the present form of my invention I have shown the casing B including a bottom section 16 or base and a top display section 17. The bottom section or base 16 includes a lower flat bottom supporting wall 18, imperforate side walls 19, and a rear imperforate wall 20. The bottom supporting wall 18, preferably, but not necessarily, extends beyond the rear and side walls of the base or bottom section and this bottom or base section houses the novel ejecting mechanism and operating mechanism C which will be later described.

The upper display section 17 extends an appreciable distance above the base section 16 and preferably includes a front glass panel 21, side glass panels 22, a top glass panel 23, and a rear glass panel 24. These glass panels are held within a suitable framework which includes upright corner standards 25 which

can be made of angle bars suitably secured through the side walls 19 of the base. The upper ends of the corner standards 25 can be connected by front and rear strips 26 and 27 and by side strips 28. These strips 26, 27 and 28 can be also angle shaped in cross section. The rear glass panel 24 is preferably carried by a hinged door structure 29 so that access may be gained into the interior of the upper section 17. It is to be noted by referring to Figure 4 of the drawings that the upper section communicates with the lower section 16 and that the front wall or panel 21 extends in back of the front portion of the base or bottom section and the portions of the base which extend beyond the vertical face of the upper section can be provided with a removable cover plate 30 formed of sheet metal or the like. This front cover plate 30 includes a depending front wall section 31 and the rearwardly extending top wall section 32. Suitable fastening elements 33 can be utilized for connecting the cover portion with the side walls. The depending front wall section 31 is provided with a longitudinally extending slot 34 adjacent to one side thereof which receives the cigar delivery chute 35. The front portion of the cover at the top edge of the slot can be bent inwardly as at 36 to provide a suitable guard to prevent the insertion of a hand into the delivery chute.

The upper section 17 is adapted to receive an entire box of cigars shown in dotted lines in Figures 1, 3 and 4 and indicated by the reference character D. The casing is of such a width as to permit the cover of the box to be swung to an open position so that the exposed cigars can be seen as well as the entire box including both sides of the cover, whereby all of the Government stamps, display notices and the like can be readily seen by purchasers operating the machine.

Referring to the cigar ejecting mechanism and the operating parts of the machine C, the same includes a metal base plate 38 which is bolted or otherwise secured to a pair of spaced transversely extending supporting cleats 39 which are in turn secured to the bottom supporting wall 18 of the base portion 16 of the casing B. The metal base plate 38 is provided adjacent to one longitudinal edge thereof with an upstanding guide flange 40 for a purpose which will be hereinafter more fully described. Secured to the bottom plate 38 in spaced relation thereto is a top plate 41, suitable bolts 42 and spacing elements 42' being employed for holding the plates in proper spaced rigid position. The top plate 41 is provided adjacent to its rear end with a cigar receiving slot 43, while the bottom or base plate 38 intermediate its ends and forwardly of the slot 43 is provided with a longitudinally extending cigar ejecting slot 44. It is to be noted that the slots 43 and 44 are not in registration at any time.

Confined between the plates 38 and 41 is the slide plate or ejecting member 45 which includes spaced side strips 46 and 47. These side plates or strips 46 and 47 are connected together by spaced intermediate strips 48 and 49 which define a pocket between the same for receiving a cigar from the box of cigars D, it being understood that the lower end of the box of cigars is torn off and the box 10 rested upon the top plate 41 over the slot 43 therein. The side plates 46 and 47 are further connected by a flat plate 50 arranged in a vertical plane which acts as a closure for the slot 43 during the ejection of a cigar from the machine, as will be later described. The forward end of the closure plate 50 is connected with the rear strip 49 at its top edge. In order to effectively guide the slide plate or cigar ejecting member during its movement, 20 the bottom or base plate 38 has secured to its top face directly below the slot 43 in the top plate 41, a guide strip 51 which terminates short of the opposite side edges of the plate and the spaced strips 48 and 49 have their 25 lower edges notched as at 52, whereby the side walls of the notches will engage the ends of the guide strip. Normally the slide plate cigar vending mechanism is in the position shown in Figure 7 of the drawings whereby 30 the plates 48 and 49 will be at opposite sides of the slot 43 to permit dropping of a cigar on the guide strip 51 and into the pocket defined by said strips or plates 48 and 49. Upon forward movement of the slide plate 35 or ejecting mechanism, the cigar will be moved forwardly with said pocket and the strips 48 and 49 will lie on opposite sides of the slot 44 in the bottom or base plate 38 allowing the cigar to drop through the slot 44 40 and into the delivery chute 35 provided for that purpose. The side plate 46 of the delivery slide engages the inner face of the flange 40 and this flange forms a guide for the same. The side plate or strip 47 of the 45 slide mechanism is provided at its forward end with a laterally extending flange 53 the rear edge of which defines a coin engaging tooth 54 as will be later described. A right angularly extending lip 55 is also carried by 50 the rear end of the plate 47, the extreme lower corner of which is notched as at 56 for a purpose which will also be described.

Operating in conjunction with the slide plate or ejecting mechanism is the operating plunger, which includes a plunger rod 57 which extends through a suitable opening 58 in the front wall 31. The rear end of the plunger rod is received in the guide notch 56 and within a guide opening formed in the 60 upstanding lip 59 carried by the bottom or base plate 38. This plate adjacent to the plunger rod is provided with a guide rib 60 therefor, for guiding the rod during its sliding movement and the rod 57 has secured 65 thereto a coin lock plate 61 which is arranged adjacent to the strip or side plate 47 of the slide plate mechanism. This coin lock plate 61 engages the flange 53 and has an inturned lip 62 at its rear end for engaging said strip or plate 47. The inner face of the coin lock plate at its upper edge and intermediate its ends, is provided with a laterally extending flange 63 which engages the outer face of the strip 47 to act as a guide for the lock plate and to also act as a closure for the registering coin slots 64 and 65 formed respectively in the cover plate 32 and the top plate 41 of the ejecting mechanism, when the plunger is in its forward operative position for ejecting a cigar. The inner face of the coin lock plate is also provided with a coin trip lug 66 which is of a substantially arcuate configuration which acts in the nature of a cam for lifting a coin toward the tooth 54 of the flange 53. A longitudinally extending guide slot 67 is formed in the coin lock plate in rear of the coin trip 66 and receives a cylindrical guide lug or boss 68 formed on the side strip 47. A suitable bolt 69 extends through the boss 68 and supports at its outer end a roller 70 for 80 engaging the plunger rod 57. Normally the plunger rod extends into the casing with its manipulating head 57' adjacent to the cover plate and the lug 62 on the coin lock plate in engagement with the stop and guide lug 55 on the slide plate 35. In this position the coin trip 66 and coin engaging tooth 54 lie on opposite sides of the coin slots 64 and 65 so that when a coin is inserted through the said 85 slots the coin will fall between the said coin trip 66 and tooth 54 and rest on the bottom or base plate between the coin lock plate 61 and the side strip 47 of the slide plate mechanism 90 45.

After a coin has been inserted in the machine and upon forward movement of the plunger rod of the operating means, the coin trip 66 will engage the coin and force the same into contact with the tooth 54 thus locking the coin lock plate and the slide plate 45 100 together as a single unit and upon continued outward movement of the plunger the slide plate 45 will be moved forwardly, consequently carrying a cigar therewith and over the slot 44 where the same will fall into the chute 35 as heretofore described. Upon release of the plunger, the coin will be released 105 and the same will drop through a coin slot 71 formed in the bottom plate for that purpose, the coin having been moved forwardly 110 over said slot by the coin lock plate and slide plate mechanism 45. The bottom plate 38 carries a depending and rearwardly extending coin chute 72 which communicates with the coin slot 71 and carries the coin rearwardly and into the coin receptacle 73. The plunger can now be returned to its normal position either manually or by spring means 115 and the lug 62 engaging the lug 55 will return the slide plate to its normal position un- 120 125 130

til the same is stopped by the combined stop and guide plate 59.

To take care of any lost motion in the plate during its travel and to normally hold the strip 46 of the slide plate 45 in engagement with the flange 40, I provide a spring pressed ball bearing member 75 which is carried by a suitable housing 76 supported by the bottom plate 38.

10 Any preferred means can be provided for supporting the box of cigars within the display portion 17 of the casing, but I prefer to provide a pair of supporting arms 77 which can be connected by means of bolts 78 to the 15 rear ends of the supporting strips or cleats 39, it being understood that the arms 77 are adjustable on the cleats in angular position. The upper terminals of the arms 77 are provided with forwardly extending ears 80 to 20 which can be connected angle iron shaped grips 81 for engaging the sides of a box of cigars. These arms 81 can also be swung about to an adjusted position and by adjusting the arms 77 and the grips 81, different 25 sizes of cigar boxes can be accommodated.

From the foregoing description, it can be seen that I have provided an exceptionally simple cigar vending machine from which cigars are ejected one at a time from the 30 original cigar box which is arranged wholly within the sight of the operator of the machine. In order to facilitate the removal of the cover plate 30, the opening 58 can be the same size as the plunger manipulating 35 head 57', so that this cover plate can be slipped over the same. This enlarged opening can be closed by a hinged plate 82 as shown in the drawings.

Changes in detail may be made without 40 departing from the spirit or the scope of this invention, but what I claim as new is:

In a cigar vending machine having a base section formed of opaque material and an upper section having front, rear and side 45 transparent panels, a cigar box holder adapted to hold said box against said front panel extending into the top section including vertically disposed arms, pivoted in the base section and being movable in a vertical plane, 50 said arms having forwardly projecting arcuate terminals, and gripping jaws, comprising angle strips, normally disposed in a vertical plane adjustably carried on pivots by the arcuate terminals of the arms, and 55 movable in a vertical plane.

In testimony whereof I affix my signature.
JOSEPH W. BEESON.
